TIRE INFLATION TESTER

Robert D. Moyer, R.F.D. 1, Box 33, Star City, Ind.

Filed June 6, 1961, Ser. No. 65,477

Term of patent 14 years

(Cl. D52—6)

The figure is a perspective view of a tire inflation tester embodying my new design.

The tester is cylindrical in shape along its full length and the end not shown is substantially the same in appearance as the end shown.

A characteristic feature of my design resides in the contrast afforded by the coincident termination and planar relationship between the end of the handle and the ferrule.

I claim:

The ornamental design for a tire inflation tester, as shown and described.
